DISCHARGE MEANS FOR COKE OVENS

Grady Padgett, Beaver, Pa.

Application June 18, 1946, Serial No. 677,557

18 Claims.

(Cl. 214—18)

1

This invention relates to means for withdrawing coke from vertical coke ovens, and has for its principal object the provision of movable apparatus for discharging coke from such ovens whenever desired with minimum loss of gases and maximum control of the falling coke.

In present practice, the lower oven door is swung away from the oven and the coke is permitted to drop several feet into a car below. This causes breakage of the coke with consequent increase of fines, and flame, smoke and dust escape into the air, with consequent waste of gases, discomfort to workmen and spreading of deleterious substances over the neighboring terrain. An object of the present invention is to do away with or materially lessen the losses and objectionable features incident to the present practice.

Another object of this invention is the arrangement in a coke-receiving car of means for unfastening and removing a sealing plate on the bottom of a vertical coke oven, loosening and moving the door supports, vertically lowering the door along with the coke at controlled speeds, guiding the movement of the coke from the lowered door to the car coke-carrying compartment, and replacing the door and sealing plate, with one placement of the car.

A further object of this invention is the provision of a hollow coupling movable into position surrounding the discharge opening of the oven and connecting the oven with a substantially dust-tight coke compartment of the car, for the purpose of sealing in the dust, flame and gases during the discharge operation.

A further object of this invention is the provision of means for horizontally moving the sealing plate and means for vertically moving the door and dust-enclosing coupling into and out of operative positions whenever desired.

A further object is the arrangement of means for accurately "spotting" or placing the coke-receiving car below the coke oven in the exact position required for proper efficient operation of the several mechanisms used in completing the discharge of coke from and resealing of the coke oven.

Various other objects and meritorious features of the invention will be apparent from the following description taken in conjunction with the drawings, wherein like reference numerals designate like parts throughout the several figures, and wherein

Fig. 1 is a side elevation of a car equipped with my improved coke discharging apparatus posi-

tioned beneath a coke oven, the side plating of the car being removed and parts being broken away to disclose the interior arrangement;

Fig. 2 is a view similar to Fig. 1 with portions of the apparatus shown in other positions assumed during operation;

Fig. 3 is a vertical cross section taken substantially on line 3—3 of Fig. 1, and showing half of the coke car;

Fig. 4 is a view similar to Fig. 3 with portions of the apparatus shown in other positions assumed during operation;

Fig. 5 is an enlarged detail sectional view through the lower extremity of the coke oven with the oven door and sealing plate in closing positions;

Fig. 6 is an enlarged detail view, showing the means for loosening (and tightening) the sealing plate in elevation at the left and in section at the right of the figure;

Fig. 7 is an enlarged detail view, showing one of the rollers carried by the sealing plate loosening means for guiding such means in its vertical and horizontal movements, such roller and supporting bracket being shown in plan at the left and in end elevation at the right of the figure;

Fig. 8 is a detail view showing the apparatus for vertically moving (and swinging) the coke oven door in another position assumed in operation, and

Fig. 9 is an enlarged detail view showing the flexible coupling arranged between motor driven operating mechanism and the means for swinging the oven door support bars out of their normal supporting positions preparatory to lowering the door.

Referring now to the embodiment illustrated herein by way of example, only the lower portion of a single vertical coke oven 10 is shown, though it is to be understood that such coke ovens are ordinarily arranged in batteries of any desired number. The walls of coke oven 10 on opposite sides of the coking chamber are formed of suitable refractory material supported at their lower extremities on strong girders 11 of I-beam construction, and cast steel frame 12 delineates the edges of discharge opening 13, forming guides for the passage of door 14 into and out of closing position. Door 14 is arranged for vertical movement and comprises suitable refractory material facing the coke within the oven, which material is supported by a horizontal metallic plate 15 in turn supported by an I-beam girder 16 of lesser height than girders 11 supporting the oven walls. To the foot of girder 16 are pivotally connected at

least a pair of spaced support bars 17 which, when turned to substantially the position shown in Fig. 1, will engage the upper faces of the bottom flanges of girder 11 and distribute the load of the door 14 and coke resting thereon to such girders 11.

To prevent escape of gases, smoke, etc., a sealing plate 18 is preferably arranged below the discharge opening 13. Such a sealing plate may be mounted in various ways, for example, as shown in my copending application Serial No. 511,618 and now Patent No. 2,475,512 granted July 5, 1949. In the illustrated embodiment of the present invention, however, I have shown sealing plate 18 mounted just below girders 11 of the coke oven (Fig. 5) with its upper face normally contacting a pair of channel irons 19 fixed to the lower flanges of girders 11, and pressed thereagainst by means of clamps 20 adapted to engage the lower flanges of channel members 21, also secured to the lower flanges of girders 11 exteriorly of channels 19 and preferably having inclined lower edges to facilitate movement of the clamps to and from clamping positions, substantially as shown. Clamps 20 are mounted for swinging movement in horizontal planes, being herein shown as fixed upon vertical stub shafts 22 journaled in brackets secured to the lower face of sealing plate 18. At its lower extremity each stub shaft 22 carries a substantially cone-shaped gear 23, which cooperates with mechanism hereinafter described for loosening and tightening the sealing plate 18 whenever desired. As best shown in Fig. 3, there are a number of clamps 20 spaced at suitable distances from each other throughout the entire width of the coke oven.

My improved means for withdrawing coke from vertical coke ovens will now be described. All of the cooperating means are preferably carried by a mobile device, such as a coke car, of appropriate width and strength adapted to be moved into position under any of the several coke ovens of a battery on suitably spaced tracks. Means are provided on the car for cooperation with switch members located adjacent the tracks for accurately "spotting" the car in correct position below any coke oven, as will be hereinafter more fully described.

Car 24 is provided with a coke compartment 25 adjacent one end thereof, and with means for loosening the sealing plate from the coke oven, and moving it to one side, means for installing a connection between car and oven to retain dust, flame, soot, etc., when the coke is being withdrawn, means for taking the load of the door and coke resting thereon from girders 11, means for swinging support bars 17 out of engagement with girders 11, means for lowering door 14 and a portion of the coke through the dust connection into car 24 at predetermined low speeds, means for swinging the door out of the way of the falling coke and moving an inclined section beneath to direct the falling coke into coke compartment 25 and, after the withdrawal of the coke from the oven, restoring the door to its former position closing discharge opening 13, replacing the sealing plate and retightening the clamps of the sealing plate.

Car 24 is shown in side elevation in Fig. 1 with its near side plating removed to show the vertical, horizontal and oblique channel members used as reinforcement, and it will be noted that I-beam girders, as 24a, are arranged across the car, with their ends incorporated into vertical channel

members, where needed, as in supporting the incline 24b forming one wall of the coke compartment of the car. It will be understood, however, that variations in the car construction and arrangement of mechanisms may be utilized as desired.

The means for removing the sealing plate from the coke oven and carrying it to one side will now be described. A frame 26 formed of I-beams is mounted for movement longitudinally of the car, as by means of flanged rollers 27 arranged between the side members of frame 26 and guide rails 28 supported at the top of the car (Figs. 1 and 3). Desired movements of frame 26 are secured by energizing the reversing motor 29 turning, through suitable reduction gearing, a gear wheel meshing with rack 30 carried by the frame. Travel limits of frame 26 may be accurately determined through chains or cables 31 unwound from or rewound upon reels 32 connected and arranged substantially as shown. The frame 26 is in an intermediate position while the car is being "spotted" beneath the desired coke oven 10 of a battery. Then the mechanism for loosening the sealing plate 18 is moved into engagement with the cone-shaped gears 23, inclined surfaces 33 being utilized to elevate such mechanism after it has been aligned. The clamp loosening (and tightening) mechanism is best shown in Figs. 1 and 6, and comprises a pair of girders 34 externally carrying rollers 35, which engage the inclined surfaces 33 of frame 26, and between which are supported a number of cup-shaped gears 36 adapted to fit over the cone-shaped gears 23 of the sealing plate clamps. The mechanism for simultaneously rotating such cup-shaped gears 36 comprises a motor 37 driving, through suitable reducing gearing, a pair of elongated shafts 38 extending across the car and carrying worm wheels 39 respectively meshing with worm gears 40 mounted adjacent the lower extremities of each of the stub shafts 41 carrying cup-shaped gears 36.

To provide a cushioned engagement between gears 23 and 36 and take-up differences in heights due to wear, warping of some of the gears, or the like, cup-shaped gears 36 may be mounted upon the stub shafts 41 substantially as shown in Fig. 6, with the upper portions of stub shafts 41 polygonal in cross section and slidingly fitting in polygonal sockets in the lower portions of cup-shaped gears 36. Springs 42 encircle such interfitting portions, their ends engaging shoulders on the gears 36 and bearing members carried by shafts 41. When the clamps 20 have been swung through substantially ninety degrees, the sealing plate 18 will be free, and may readily be moved from below the discharge opening of the coke oven to a position at one side thereof. This is accomplished by moving the frame 26 and rack 30 to the right, as from the position shown in Fig. 1 to substantially the position shown in Fig. 2. The rollers 35 will roll down the inclined surfaces 33, lowering the clamp loosening mechanism and sealing plate simultaneously. When the rollers 35 engage abutments 43 of the frame the lowering movement ceases and the sealing plate will be transported to the right simultaneously with the frame 26.

Such travel of the frame 26 in transporting the sealing plate 18 to one side is also utilized for bringing the upper section 44 of a dust coupling into alignment with the lower section 45 of the dust coupling and with the coke oven 10. As illustrated in Fig. 1, rollers 46 on the upper section

44 normally rest in contact with abutment 43 and adjacent inclined surfaces 47 of the frame 26, such surfaces 47 being inclined in the opposite direction from that of inclined surfaces 33 with which the clamp loosening and clamping mechanism is operated. In such normal position, the upper section 44 of the dust coupling will be transported by frame 26 until the lower edges of upper section 44 are brought into engagement with the upper edges of the lower section 45 of the dust coupling. The two sections may be made to fit quite snugly and effectively prevent escape of gases, smoke, flame, etc., at this point, as by inbending the upper portion of lower section 45 to form a groove receiving the lower portion of upper section 44. Suitable packing is provided on either or both sections of the dust coupling.

Lower section 45 of the dust coupling is mounted on the framework of the car in such a manner that it is capable of sliding vertically for limited distances. Accordingly, after upper and lower sections 44 and 45 have been joined by movement of frame 26, then further movement of such frame to the right will tend to bring inclined surfaces 47 under rollers 46 to elevate both sections of the dust coupling until engagement is made with the channel members 21 which had formerly supported the sealing plate 18. A substantially horizontal surface is provided at the upper extremities of inclined surfaces 47 to enable maintenance of the dust coupling in raised position while the coke oven is being discharged. It will be understood that the dust coupling extends laterally beyond the sides of the coke oven discharge opening, and the walls thereof are separated sufficiently to permit vertical movements of the door 14 and door operating mechanism, as well as the falling coke, through the dust coupling. A flange 45a is provided at the lower extremity of lower coupling section 45, and packing 45b (Fig. 1) is positioned to be engaged by such flange 45a whenever the dust coupling is elevated. A flexible flap 45c may also be provided between the packing 45b and rail 48, hereinafter described, to retain dust, smoke, etc., within the coke compartment 25 of the car.

The means for lowering door 14 into car 24 through the dust coupling will now be described. A door lifting and lowering member 49 is mounted within the car so as to be raised into engagement with girder 16 of door 14, then raised slightly further to relieve support bars 17 of the weight of the door and coke resting thereon, and then, after the support bars 17 have been swung out of engagement with girders 11, such member 49 is lowered simultaneously with door 14 and the charge of coke. As best shown in Figs. 1, 3, and 8, door lifter 49 comprises a framework guided for vertical movements within spaced U-shaped guide frames 50, the upper portion of door lifter 49 being forked, with the tines spaced from each other a sufficient distance to enable straddling of the lower flange of girder 16 carrying oven door 14. A cross bar at the bottom of the forked portion of the door lifter engages the foot of girder 16 when the door lifter is sufficiently raised, and slight further elevation will transfer the weight of door 14 and coke resting thereon onto door lifter 49, relieving support bars 17 and girders 11 of such weight.

Vertical movements of member 49 are secured from motor 51 driving, through suitable reduction gearing, a gear wheel 52 meshing with a rack 53 on door lifter 49. It will be understood that

at least two of such door lifters 49 are provided in each coke car, and that Figs. 3 and 4 herein illustrate only half of such coke car, the remaining half, however, being a substantial duplicate of the showing herein. Motor 51 may drive an elongated shaft 51a (Fig. 3) operating reduction gearing elements for each door lifter mechanism, so that raising and lowering of all the door lifters 49 in the car will proceed simultaneously. The U-shaped guide frames 50 of each elevator mechanism are pivotally mounted adjacent their lower extremities substantially as shown in Figs. 1 and 3, the pivot shaft 54 being journaled in appropriate bearings carried by the car. Means are provided for rocking door lifters 49 and guide frames 50 on pivots 54 whenever desired. As herein shown, a motor 55 drives through suitable reduction gearing pinion 56, meshing with rack 57 pivotally connected at one extremity with the upper portion of frame 50 of the door lifter mechanism. The two or more door lifters 49 carried by car 24 are connected to each other by a plurality of channel members 58 (Fig. 3) to insure simultaneous rocking movements of all door lifters.

Means for turning support bars 17 whenever desired are also carried by channel members 58, and preferably comprise forked turning members 59 mounted at the upper extremities of rods 60 journaled for rotary movement in suitable bearings. A motor 61 is mounted on the lower channel member 58 connecting door lifters 49, and appropriate reduction gearing is provided between the motor and rod 60 to slowly turn fork member 59 when desired. A flexible coupling 62 may also be arranged between upper and lower portions of each rod 60 to accumulate power from the motor and soften somewhat the swinging movements of the support bars 17. In Fig. 9 is shown such a flexible coupling wherein the upper and lower sections of rod 60 are joined together through a strong spring 63 secured at its ends to a plate 64 carried by the upper rod section and a cage 65 carried by the lower section of rod 60, plate 64 being guided in slight vertical movements relatively to cage 65.

After freeing door 14 from girders 11 of the coke oven by swinging support bars 17 a sufficient distance through operation of fork members 59, the coke oven door 14 with its attached girder 16 and support bars 17 are lowered at relatively slow speeds through the dust coupling and into car 24, a portion of the coke within the oven lowering simultaneously with the door. When door lifters 49 have reached their lowermost positions, the upper surface of door 14 will have reached a position within the car just below channel 48 extending laterally across the car. Then when motor 55 is energized to rock the door lifter mechanisms, door 14 is swung to the left in Fig. 1 so as to remove it from the path of the sliding coke. Channel 48 operates as a stationary rake to hold back the coke as door 14 is swung. Simultaneously an inclined chute section 24c (Fig. 1), which is carried by the door lifter frames 50 is moved into the position just occupied by oven door 14. Inclined chute section 24c bridges the span between the upper extremity of inclined floor 24b of coke compartment 25 of the car and channel 48. Coke will now discharge from coke oven 16 in a comparatively smooth movement, sliding down the inclined chute section 24c and floor 24b, into coke compartment 25. Preferably the length of the inclined floor por-

tion of the coke compartment 25 is substantially equal to the height of the oven, and a sufficiently steep incline is provided to avoid retarding movement of the coke, since the head of its fall will constantly decrease. A reverse incline 24d is provided in the floor at the opposite side of coke compartment 25, the falling coke passing over door 24e, through which the coke may be deposited whenever desired. This comparatively gentle discharge of the coke from coke oven 10 results in a minimum of breakage and assists in reducing many of the disagreeable features ordinarily incident to the discharge of coke ovens. Thus the noise is lessened, and the escape of gases, smoke, flame, etc., is checked.

The means for "spotting" the coke car in exact position below the oven desired to be discharged is shown diagrammatically in Fig. 1. A switch member 66 pivotally mounted upon the car is adapted to be lowered into contact with a stationary switch member 67 located adjacent the track and forming part of a light circuit and/or indicator circuit, which includes a light or other indication at the top of the oven below which the car is being "spotted." This indication at the top of the oven is to prevent accidental charging of the oven at the wrong time or opening of doors or valves during the discharge operation. Obviously many forms of switches and/or indicators may be utilized, so that a diagrammatical showing is believed to be sufficient herein.

An electric switchboard 68 is also shown diagrammatically in Fig. 1. Various switches may be arranged and connected for operating various motors, as motors 29, 37, 51 and 55, in their proper sequence. An operator seated adjacent switchboard 68 may throw the desired switches at will.

From the above it will be obvious that I have provided a mobile unit carrying all of the necessary apparatus for carrying out the various steps required in discharging coke oven 10 whenever desired at a single placement of such mobile unit. It will be noted that inclined surfaces 33 and 47 are designed with their intermediate portions steep to effect a rapid raising or lowering of the mechanism for loosening (or tightening) the clamps of the sealing plate 18 or dust coupling 44, 45, whenever desired, while the lower and upper portions of such inclined surfaces are comparatively flat to effect a very slow movement of such mechanisms at the ends of travel. Many other advantages and meritorious features will be apparent to those skilled in the art, and it is to be understood that the present disclosure is subject to variation and modification within the spirit and scope of the subjoined claims.

I claim:

1. In discharge means for a coke oven having a discharge opening normally closed by a vertically movable door latched in closing position, the combination of means for unlatching said door, and means for lowering said unlatched door from its normal closing position and simultaneously lowering the coke from within the oven at controlled speeds, said last-mentioned means being mounted for swinging movement out of the path of the falling coke during the discharge of the oven.

2. In discharge means for a coke oven having a discharge opening normally closed by a vertically movable door latched in closing position, the combination of means elevatable into position contacting said door to preliminarily lift said door, and means for unlatching said door while in such lifted position, said first-mentioned means then lowering said unlatched door and a portion

7
8
of the coke from within the oven at controlled speeds.

3. In discharge means for a coke oven having a discharge opening normally closed by a vertically movable door latched in closing position, the combination of means elevatable into position contacting said door to preliminarily lift said door, and means for unlatching said door while in such lifted position, said first-mentioned means then lowering said unlatched door and a portion of the coke from within the oven at controlled speeds, both of said means being movable to and from a position directly below said oven.

4. In discharge means for a coke oven having a discharge opening normally closed by a vertically movable door latched in closing position and a plate latched in sealing position below the door, the combination of means for unlatching said sealing plate and moving it from the path of movement of the door, means for unlatching said door, and means for lowering said unlatched door from its normal closing position.

5. In discharge means for a coke oven having a discharge opening normally closed by a vertically movable door latched in closing position and a plate latched in sealing position below the door, the combination of means for unlatching said sealing plate and moving it from the path of movement of the door, means for unlatching said door, and means for lowering said unlatched door from its normal closing position, said last-mentioned means being arranged to swing said lowered door out of the path of movement of the discharging coke.

35 6. Discharge means for coke ovens of the character described comprising means for unlatching the oven discharge door, means elevatable into position contacting said door, holding said door while it is being unlatched, and then lowering said door and a portion of the coke from within the oven at controlled speeds, and means for guiding the discharging coke as it falls from the oven.

7. Discharge means for coke ovens of the character described comprising means for unlatching the oven discharge door, means elevatable into position contacting said door, holding said door while it is being unlatched, and then lowering said door and a portion of the coke from within the oven at controlled speeds, and means for guiding the discharging coke as it falls from the oven, all of said means being mounted for movement into position directly below the coke oven.

8. Discharge means for coke ovens of the character described comprising means for unlatching the oven discharge door, means elevatable into position contacting said door, holding said door while it is being unlatched, and then lowering said door and a portion of the coke from within the oven at controlled speeds, means for guiding the discharging coke as it falls from the oven, and a dust-enclosing casing movable into a position surrounding said means during the door lowering operation.

65 9. A coke discharge car for withdrawing coke from a coke oven of the character described, said car having a coke-receiving compartment, and comprising means for unlatching the coke discharge door of the oven, means for lowering the unlatched door from its normal closing position and simultaneously lowering a portion of the coke from within the oven at controlled speeds, and means for then guiding the falling coke into said coke-receiving compartment.

70 10. A coke discharge car for withdrawing coke

from a coke oven of the character described, said car having a coke-receiving compartment, and carrying means elevatable into position supporting the coke discharge door, means for unlatching said door while supported by said first-mentioned means, said first-mentioned means being then lowerable to lower said unlatched door and a portion of the coke from within the oven at controlled speeds, means for swinging said door out of the path of movement of the discharging coke, and means for guiding the discharging coke into said coke-receiving compartment.

11. A coke discharge car for withdrawing coke from a coke oven of the character described, said car having a coke-receiving compartment, and carrying means elevatable into position supporting the coke discharge door, means for unlatching said door while supported by said first-mentioned means, said first-mentioned means being then lowerable to lower said unlatched door and a portion of the coke from within the oven at controlled speeds, means for swinging said door out of the path of movement of the discharging coke, and means for guiding the discharging coke into said coke-receiving compartment, said coke car also carrying a dust-enclosing housing movable into position surrounding the discharge opening of the oven and the lowering door during the discharge operation.

12. In discharge means for a coke oven having a discharge opening normally closed by a vertically movable door latched in closing position, and a plate latched in sealing position below the door, the combination of means movable into position below the oven for unlatching said sealing plate, and means for moving the unlatched sealing plate to one side.

13. A coke discharge car for withdrawing coke from a coke oven of the character described, having a latched sealing plate, said car carrying a movable frame, means for unlatching said sealing plate mounted on said frame for movement therewith and also for movement relatively to said frame, and means for moving said frame.

14. A coke discharge car for withdrawing coke from a coke oven of the character described, having a latched sealing plate, said car carrying a movable frame, means for unlatching said sealing plate mounted on said frame for horizontal movement with the frame and also for vertical movement relatively to the frame, and means for moving said frame.

15. A coke discharge car for withdrawing coke from a coke oven of the character described, said car carrying a dust-enclosing casing having a plurality of sections, one section being mounted for vertical movement only, a movable frame mounted on the car, and a section of said dust-enclosing casing mounted on said frame for horizontal movement with the frame and also for vertical movement relatively to the frame, and means for moving said frame.

16. A mobile unit for discharging coke from a coke oven having a discharge opening normally closed by a vertically movable door latched in closing position and a plate latched in sealing position below the door, said mobile unit carrying means for unlatching and removing said sealing plate, means for unlatching said door, means for lowering said unlatched door and the coke from within the oven, means for swinging said door out of the path of the discharging coke, and means for guiding the discharging coke to a desired location.

17. A mobile unit for discharging coke from a coke oven having a discharge opening normally closed by a vertically movable door latched in closing position and a plate latched in sealing position below the door, said mobile unit carrying means for unlatching and removing said sealing plate, means for unlatching said door, means for lowering said unlatched door and a portion of the coke from within the oven, and means for swinging said door out of the path of the discharging coke, said means being reversible in action, whereby said door and sealing plate may be returned to their normal positions and re-latched in such positions during a single placement of said mobile unit.

18. A mobile unit for discharging coke from a coke oven having a discharge opening normally closed by a vertically movable door latched in closing position and a plate latched in sealing position below the door, said mobile unit carrying means for unlatching and removing said sealing plate, means for unlatching said door, means for lowering said unlatched door and a portion of the coke from within the oven, and means for swinging said door out of the path of the discharging coke, an inclined chute carried by said mobile unit for guiding the discharging coke, said last-mentioned means being connected and arranged to swing into the path of the discharging coke a section of said inclined chute.

GRADY PADGETT.
